UNITED STATES PATENT OFFICE.

FRANK O. KING, OF GLENCOE, ILLINOIS.

DESIGN FOR A DOLL.

Application filed January 30, 1926. Serial No. 16,340. Term of patent 3½ years.

To all whom it may concern:

Be it known that I, FRANK O. KING, a citizen of the United States, residing in the village of Glencoe, in the county of Cook and State of Illinois, have invented a new, original, and ornamental Design for a Doll, of which the following is a specification, reference being had to the accompanying drawings, forming part hereof, Figure 1 of which is a side view and Figure 2 of which is a view of the opposite side of the doll.

I claim:

The ornamental design for a doll substantially as shown.

FRANK O. KING.
